UNITED STATES PATENT OFFICE.

ROBERT STIRLING, OF DORMANS PARK, ENGLAND.

APPARATUS FOR CONTROLLING OIL WELLS.

Application filed April 26, 1924. Serial No. 709,100.

To all whom it may concern:

Be it known that I, ROBERT STIRLING, of The Anchorage, Dormans Park, Surrey, England, a subject of the King of Great Britain and Ireland, have invented certain new and useful Improvements in and Relating to Apparatus for Controlling Oil Wells, of which the following is a specification.

- 10 This invention relates to apparatus employed to control oil wells and the like, known as a "blow-out preventer". It is chiefly adopted, when drilling a well by the "rotary system", as a packer to prevent the escape of oil and gas and the like between the drill stem pipe and the casing pipe, but is also of general use between the various sizes of casing pipes used to line boreholes.
- 15 The object of the invention is to provide an effective and simple blow-out preventer or packer held in position so that it can be readily applied when required to prevent the escape of oil or gas or other liquid or fluid under pressure between the pipes used in drilling or casing boreholes.

Apparatus embodying my invention enables the packing piece to be readily withdrawn when it is required to allow a coupling of the rotary drill stem or casing pipe to pass, without disturbing the packing, and retains it in position to be easily and quickly returned when the coupling has been passed in or out. The packing ring 35 is not brought into use until required, and can, therefore, be used to pass any number of couplings without being deformed, and is consequently ready to make a perfect joint between the drill stem and casing pipes, or between casing pipes of different sizes, against any pressure, when required to prevent leakage.

Therefore, apparatus constructed in accordance with the invention comprises, essentially, a sectionally-constructed member provided with packing and capable of radial and longitudinal movement relatively to the drill pipes, casing pipes or the like, and means for accomplishing the operation 50 of the member.

Referring to the drawings filed here-with;—

Fig. 1 is a sectional elevation of one construction of the apparatus;

55 Fig. 2 is a plan showing the packer in position to make a joint, and the positions

of the segments, when opened, to pass a coupling; and

Fig. 3 is a detail fragmentary vertical section through one of the screw pins used to retain the packing ring in position.

Figs. 1 and 2 illustrate the apparatus in position to make a tight joint between the drill stem pipe A and the casing pipe B. C is the seating or "casing head" attached by screw to the casing B. It is provided with four outlets D, to any or all of which pipes, controlled by valves, can be screwed to take away gas or liquid when required. The hinged packing segments E, held by the studs G having nuts L and pins M, are shown in position to make a tight joint, and in Fig. 2 is represented also the open position E' of the segments to allow the coupling F to pass. They are prevented from opening further by the stop pins H screwed into the top of the seating C. Handles I are provided to lift and operate the segments easily. The method of holding the packing ring J in position, by the four screw pins K, is shown in Fig. 3.

The apparatus may be operated in the following manner;—

When it is required to pass the coupling F, the nuts L are run to the tops of the studs G against the pins M. The segments E are then lifted up to the nuts by the handles I, and opened, until stopped by the pins H, and retained resting on the top of the seating C, as shown in Fig. 2 at E'. When the coupling F has been passed, the segments E are closed and dropped into the position shown in Fig. 1, the nuts L being run down the studs G by hand to their original positions. This operation can be repeated, as often as a coupling has to be passed, without displacing or deforming the packing ring J, which consequently remains in condition to make a tight joint when required. When it is required to make a tight joint, the nuts L are screwed down by aid of a wrench, thus expanding the packing ring J, which is preferably made of soft lead, but may be of elastic material.

What I claim and desire to secure by Letters Patent is;—

1. A blow-out preventer for oil-well casings comprising sections carrying joint-making packing for co-acting with the inner casing, said sections being hinged at one

end on means fixed to the outer casing, being adapted to abutably engage and disengage other means also fixed on said outer casing, and being slideable longitudinally of, and over, both said means; and devices operatively positioning said sections relatively to said means.

2. A blow-out preventer for oil-well casings comprising a head secured to the outer casing, and having at least one delivery pipe associated with it; sections carrying joint-making packing for co-acting with the inner casing, said sections being hinged at one end on means fixed to said head, being adapted to abutably engage and disengage other means also fixed on said head, and being slideable longitudinally of, and over, both said means, and devices operatively positioning said sections relatively to said means.

3. A blow-out preventer for oil-well casings comprising a head secured to the outer casing; complementary arcuate sections co-acting with the inner casing; joint-making packing carried by said sections; means on said head with which the sections are constrainedly associated so that they may turn radially towards, and from, said inner casing to close around and embrace it to make a tight joint, or separate and release it, as well as move vertically and lengthwise of said casing in order to permit the passage of couplings thereon; and devices operatively positioning the sections relatively to said head and to said means.

4. A blow-out preventer for oil-well casings comprising a head secured to the outer casing and having a socket at the end remote from said casing; complementary arcuate sections co-acting with the exterior of the inner casing and having spigot portions co-operating with the socket of said head; joint-making packing carried by said spigot portions; members fixed to, and projecting from, said head, said members serving for the pivoting of said sections and for their abutting contact, as well as constituting guides for their vertical movement; and means on said members and on said head for operatively positioning said sections.

5. A blow-out preventer for oil-well cas-

ings comprising a head secured to the outer casing and having a socket at the free end; two studs fixed to said head at opposing locations; a pair of complementary arcuate members adapted to pivot relatively to said studs as well as slide thereover; eyes at one end of said members hingably engaging one of said studs so that the members close and open radially with regard to the inner casing and thus jointly embrace and release same; ears at the other end of said members engaging and disengaging the other said stud; means on said members for sliding them vertically over said studs to raise and lower them relatively to said head; spigot portions on said members complementary to the socket in said head; joint-making packing carried by said spigot portions; and nuts on said studs for locking and releasing said members relatively to said head.

6. A blow-out preventer for oil-well casings comprising a head secured to the outer casing, said head having a socket at the free end, and having at least one delivery pipe communicating with the space between said outer casing and the complementary inner casing; two studs fixed to said head at opposite points; a pair of complementary arcuate members adapted to pivot relatively to said studs, as well as slide thereover lengthwise; eyes at one end of said members hingably engaging one of said studs so that the members close and open radially with regard to said inner casing and thus jointly embrace and release same; ears at the other end of said members engaging and disengaging the other of said studs; means on said members for sliding them vertically over said studs to raise and lower them relatively to said head; spigot portions on said members complementary to the socket in said head; joint-making packing carried by said spigot portions; nuts on said studs for locking and releasing said members relatively to said head; means on said studs for limiting the inoperative movement of said nuts; and stops on said head for determining the amount of opening of said members.

In testimony whereof, I affix my signature.

ROBERT STIRLING.
